UNITED STATES PATENT OFFICE.

PIERRE PLANTINGA, OF CLEVELAND, OHIO; THE CLEVELAND TRUST COMPANY
EXECUTOR OF SAID PIERRE PLANTINGA, DECEASED.

CARBONIZING AND GAS-MAKING APPARATUS.

Application filed December 21, 1922. Serial No. 608,203.

My invention relates to carbonizers used in gas-making apparatus, its object being to provide a device of said character which is simple in construction and efficient in its operation.

The said invention consists of means hereinafter fully described and particularly set forth in the claims.

More specifically, my said invention consists of a modified form of the apparatus shown, described and claimed in my application Serial No. 601,680; filed November 18, 1922.

In the annexed drawing, the figure represents, diagrammatically, a side elevation of a carbonizer embodying my invention.

In the illustrated embodiment of said invention, a gas-producer 1, is provided of the usual construction, having a primary air-inlet 2 and a steam-inlet 3 at the bottom, and a secondary air-inlet 4 at the top so that the gas may be burned in such top, which forms a combustion chamber. Above the producer is an open arch 5 which supports checker-work 6 which fills a heat-absorbing and transmitting element 7.

The top part of the producer, that is the combustion chamber, communicates with the bottom portion of a carbonizing chamber 8 through the medium of a pipe-connection 9 and the top portion of the said carbonizer is connected with the inlet side of a blower or fan 10, by means of a pipe-connection 11. The outlet side of said blower is connected 35 with the top portion of the element 7 by means of a pipe-connection 12 controlled by a valve 13. A branch 14 leads from the connection 12 to other parts of the gas-making apparatus (not shown) as will be readily understood by those skilled in the art.

The top of the carbonizing chamber is provided with a charging inlet 15 and closure 16 therefor as shown, and the bottom with a discharging outlet 17 and a suitable closure 18.

The top of the element 7 is provided with an outlet 19 controlled by a suitable stack-valve 20 below the stack 21.

Intermediately of the blower 10 and the branch pipe 14 is a valve 22.

In operating the above described apparatus, assuming that the producer 1 is charged with burning fuel and the carbonizer charged with coal, the valves 13 and 22 are closed and the stack-valve 20 opened; primary air and the required amount of steam

are admitted to the producer through the inlets 2 and 3 and producer gas is thereby generated by the producer 1. Secondary air is admitted through the inlet 4 and the producer gas is burned in the top portion or combustion chamber of the producer. The gases of combustion rise, pass through the checker-work 6, impart their heat thereto and then pass out through the opening 19 into the stack 21.

When the checker-work is sufficiently heated, the primary and secondary air and steam are turned off, valves 13 and 22 opened and the stack valve 20 closed. The blower is then started and the gaseous content of the apparatus is caused to circulate through same. Such gases in passing through the checker-work become highly heated and then pass into the bottom of the carbonizer, upwardly through the coal therein. These hot gases distil such coal with a resultant production of coal gas which passes with such heated gas out through pipe 11, through blower 10, pipe connection 12 and back into the element 7.

Superfluous gas passes out through the branch pipe 14.

The above described process continues until the temperature of the checker-work 6 is below that required to impart a distilling temperature to the gases, whereupon the blower is shut off, valves 13 and 22 closed, and stack-valve 20 opened.

The primary and secondary air and steam are again turned on, the checker-work re-heated as before, and the previously described subsequent procedure carried out.

By means of the above described apparatus gases of various kinds may be obtained.

During the process of distillation, the primary air and steam may be cut off and only coal gas produced. By turning on the primary air and the required amount of steam, a mixture of coal-gas and producer gas may be obtained. By turning on the primary air and more steam a mixture of coal-gas, producer gas and water gas may be had. By shutting off the primary air and passing steam only through the producer, a mixture of blue water-gas and coal-gas is secured.

These different gases may therefore be produced and if it is desired to segregate any one or more of them, they may be conducted to suitable separate receivers, as will be understood by those skilled in the art.

It will be understood that a continuous operation of the producer for the purpose of supplying gas to be burned for generating heat to heat the checker-work, may be obtained by adding one or more elements 7 and suitable valve-controlled connections, as is shown and described in my above-mentioned pending application.

What I claim is:

16. 1. A carbonizing and gas-making apparatus comprising a heat-absorbing and transmitting element; heat-generating means including a gas-producer, beneath and connected with said element; a primary-air inlet 15 for the lower part of the producer and separate means for admitting steam to such producer part; a secondary air inlet for the upper part of said producer; a carbonizing chamber separate from said producer and 20 said element but communicating with both of same; and means for effecting a circulation of gases through said element and carbonizing chamber.
  25. 2. A carbonizing and gas-making apparatus comprising a heat-absorbing and transmitting element; heat-generating means including a gas-producer, beneath and connected with said element; an air inlet for the lower part of said producer and separate 30 means for admitting steam to such producer
- part; a carbonizing chamber separate from said producer and element; means establishing communication between the upper part of said carbonizing chamber and the upper part of said element; means establishing 35 communication between the lower part of said chamber and the lower part of said element; and a blower in the first-mentioned communicating means for effecting a cyclic circulation through and between the said 40 element and carbonizing chamber.
3. A carbonizing and gas-making apparatus comprising a heat-absorbing and transmitting element; a gas-producer below said element and having its bottom communicating with the top of said producer, the latter being provided with the usual primary-air and steam inlets and also provided at the top part thereof with a secondary-air inlet; a carbonizing chamber separate from the said producer and element; a conduit connecting the bottom of said chamber with the top of said producer; a conduit connecting the top of said element with the top of said chamber; and a blower in one of said 45 conduits for effecting a cyclic circulation of gases through said element and chamber.

Signed by me this 9th day of December, 1922.

PIERRE PLANTINGA.
